(57) **CLAIM**

The ornamental design for the food product, as shown and described.

DESCRIPTION

FIG. 1 is an isometric view of the food product.

FIG. 2 is a top plan view of the food product of FIG. 1.

FIG. 3 is a bottom plan view of the food product of FIG. 1.

FIG. 4 is a first side elevation view of the food product of FIG. 1; and,

FIG. 5 is a first end elevational view of the food product of FIG. 1.

The broken lines in FIGS. 1 and 4 illustrate portions of the food product which form no part of the claimed design.

The food product includes a second side elevational view that is identical to the first side elevational view represented in FIG. 4. The food product also includes a second end elevational view that is identical to the first end elevational view presented in FIG. 5.
